UNITED STATES PATENT OFFICE.

CHARLES JOHN ARMSTRONG, OF AUSTIN, TEXAS.

GEARING FOR CHURNS AND ICE-CREAM FREEZERS.

1,201,234.

Specification of Letters Patent. Patented Oct. 17, 1916.

Application filed July 24, 1915. Serial No. 41,753.

To all whom it may concern:

Be it known that I, CHARLES J. ARMSTRONG, citizen of the United States, residing at Austin, in the county of Travis and State of Texas, have invented a new and useful Gearing for Churns and Ice-Cream Freezers, of which the following is a specification.

This invention relates to an improvement in churns and ice cream freezers.

The object is to provide means for operating the dasher or agitator of a churn or ice cream freezer, which is capable of being swung into and out of position at the will of the operator.

The invention consists of certain novel features of construction and combinations of parts which will be hereinafter described and pointed out in the following claims; it being understood that changes in the form, proportion, material and minor details of construction, within the scope of the appended claims, may be made without departing from the spirit or sacrificing any of the advantages of this invention.

In the accompanying drawings, Figure 1 is a view in elevation of the invention showing a portion of the apparatus in section. Fig. 2 is a detail view in elevation showing the connection between the standard or post and bracket. Fig. 3 is a horizontal sectional view on the line 3—3 of Fig. 1. Fig. 4 is a horizontal sectional view on the line 4—4 of Fig. 1. Fig. 5 is a horizontal sectional view on the line 5—5 of Fig. 1. Fig. 6 is a horizontal sectional view on the line 6—6 of Fig. 1. Fig. 7 is an enlarged vertical sectional view showing the mechanism for operating the dasher and agitator. Fig. 8 is a top plan view of the support for the ice cream freezer or churn receptacle. Fig. 9 is a view in elevation of the detachable legs of the support shown in Fig. 8. Figs. 10 and 11 are views in top plan of the agitators or blades of the churn, and Fig. 12 is a view in section of an ice cream freezer showing the invention in elevation applied thereto.

A represents the churn receptacle which is supported upon a base 1 having a recess 2 formed therein for the reception of the receptacle A. A leg 3 is connected to the base for forming a support therefor, and legs 4—4 are connected at their inner terminals to a plate 5. The plate 5 is adapted to be connected to a plate 6, which extends down-

wardly from the base 1, by means of bolts 7 and nuts 8. The inner surfaces of the plates 5 and 6 are preferably concaved, forming a channel or socket for an end of a standard or post 9. The bolts 7 and nuts 8 clamping the plates 5 and 6 together, securely fasten the lower terminal of the standard or post 9 to the plates, while the legs 3 and 4 form a support for the base 1 and post 9.

Connected to the upper terminal of the standard or post 9 are clamping members 10 and 11. These members are held upon the post by means of bolts 12 and nuts 13. The clamping member 10 is provided with a recess 14, which is preferably made arc shape. Mounted in the recess 14 is the lower terminal or ear 15 of a bracket B. The surface of the terminal 15 is rounded to conform to the shape of the recess and shoulders are formed on the bracket, as at 16, for engaging shoulders 17 formed on the clamping member 10 to limit the rotary movement of the bracket on the clamping member.

A recess 18 is formed in the bracket B in which the upper terminal or ear of the clamping member 10 is received. A bolt 19 passes through the lower terminal 15 of the bracket B, and the upper terminal of the clamping member 10, and a wing nut 20 is screwed upon the bolt for fastening the clamping member 10 and the bracket together, the adjustment of the wing nut 20 regulating the angle at which the bracket may be held upon the clamping member 10.

Connected to the bracket B are upper and lower arms 21 and 22 which are spaced apart. Connected to the upper arm 21 is a rotatable shaft 23. Collars 24 are connected to the shaft above and below the arm 21 for supporting the shaft upon the arm. The arm 22, as may be best seen from Fig. 7, is provided with an opening 25 through which the shaft 23 extends. A bevel pinion 26 is loosely mounted upon the shaft 23 and is supported upon the upper surface of the arm 22. A hub 27, connected to the bevel pinion 26, extends through the opening 25 in the arm 22 and is connected to a sleeve 28 by a screw 29. A bevel pinion 30 is rigidly mounted upon the upper end of the shaft 23 and is adapted to rotate therewith. A horizontal shaft 31 is mounted on the bracket B and has a bevel gear 32 connected thereto. The bevel gear 32 meshes with the bevel pinions 26 and 30 for causing the rotation of 110

the pinions upon the rotation of the shaft 31, by means of a crank handle 33 or other suitable means.

A hub 34 is connected to the lower terminal of the shaft 23 and is provided with a square opening 35 in which is received the squared end 36 of the agitator or dasher shaft 37. The lower terminal of the dasher shaft 37 is mounted in a stepped bearing 38', and connected to the lower terminal of the shaft 37 are a plurality of vertical blades 38 which radiate from a hub 39. These blades 38 are slightly curved and at their inner terminals and on the upper sides thereof they are cut away, as at 40, for forming a bearing for a tubular shaft or member 41 which surrounds the shaft 37. The hub 39 of the blades 38 is located below the lower edge of the tubular member 41 so that an air outlet is formed between the blades and between the lower terminal of the tubular member 41 and hub 39.

Connected to the lower terminal of the tubular member 41, are a plurality of obliquely curved blades 42. A hub 43 is connected to the upper terminal of the tubular member 41 and is provided with a reduced outer portion which has its outer surface squared, as at 44, to receive the squared inner surface 45 of the sleeve 28. The shaft 37 extends through the hub 43 and has free rotary movement therein. When power is applied to the shaft 31, rotary motion is transmitted to the vertical shaft 23 and to the sleeve 28 through the bevel pinions 30 and 26 respectively. The rotation of the shaft 23 causes the shaft 37 to be rotated, and the rotation of the sleeve 28 causes the tubular member 41 to be rotated in an opposite direction to the shaft 37, thereby causing the blades 38 and 42 to be rotated in opposite directions for producing a churning operation. As the blades are rotated, air is sucked or drawn through the openings 46 located at the upper end of the tubular member 41, down through the tubular member 41, and discharged at the lower terminal thereof between the blades 38 thereby aerating the cream. By locating the blades 38, and 42 in close proximity, and rotating them in opposite directions, the whirl which is generally transmitted to the cream, causing it to be thrown out at the top of the churn or receptacle A, is eliminated, since the blades, due to their location with respect to each other, will counteract the whirl.

The curved vertical blades 38 on the shaft 37, and the obliquely curved blades 42 of the tubular member 41, rotate in opposite directions. The blades 38 will throw the cream outwardly and create a whirl in one direction, and the blades 42 will throw the cream outwardly and upwardly and create a whirl in an opposite direction to the whirl created by the blades 38. This action on the

cream by the blades 38 and 42 causes the air to be sucked or drawn downwardly through the tubular member 41, thereby thoroughly aerating the cream and producing a fine grade of butter in a short time. The shaft 37 and tubular member 41 can be easily separated as they are not fastened together, and when separated a brush can be inserted in the tubular member for cleaning the same, as there are no obstructions in the tubular member to interfere with the cleaning operation.

In Fig. 12 I have shown the apparatus applied to an ice cream freezer which consists of a tub 47 mounted on the base 1, and a can or tubular member 48 mounted within the tub 47 and journaled in a step bearing 49. A dasher or agitator 50 is mounted upon the shaft 37 instead of the blades 38. The shaft 37 is connected to the hub 34 in the same manner as when applied to a churn, and a cover 51 is mounted upon the can or tubular member 48 and is provided with a hub or annular bearing 52, the annular bearing 52 being provided with a squared bore to engage the squared outer surface 53 of the sleeve 28. When the shaft 23 and sleeve 28 are rotated, the shaft 37 and dasher 50 will be rotated in one direction, and the can or tubular member 48 will be rotated in an opposite direction. When it is desired to disengage the bracket B from either the ice cream freezer or churn, the wing nut 20 is rotated upon the bolt 19, so that the frame B can be rotated. As the frame is swung upwardly the sleeve 28 will become disengaged from the tubular member 41 or 48, as the case may be, and the hub 34 on the vertical shaft 23 will become disengaged from the shaft 37. In this way the bracket may be swung for connecting it to the dasher or blades, or disconnecting it therefrom at any time. When the bracket has been swung to a position so that it is out of engagement with the blades or dasher of the churn or freezer, the dasher or blades may be removed or inserted. It will be seen that the connection between the bracket and dasher or blades can be made, or the brackets separated therefrom, without the necessity of removing the bracket from its support.

From the foregoing it will be seen that I have provided an apparatus which can be assembled and operated readily and the various parts of the churn and freezer can be separated and thoroughly cleansed. The tubular member 41 of the churn is not provided with any obstructions which would interfere with the thorough cleaning of the same. As the bearings become worn the bracket B can be lowered upon the post or standard 9 by means of the clamping members 10 and 11, or the bracket may be elevated for the purpose of accommodating it to the various sizes of churning or freezers.

What is claimed is,—

1. In mechanism as specified, a support, concentric driven members on the support, a bracket hinged for edgewise swinging adjustment on the support, a pair of drive members in the bracket, and interfitting concentric connections between the drive and driven members and being located inwardly of the pivotal connection of the bracket with the support whereby the drive and driven members may be separated by the outward swinging of the bracket.

2. In mechanism as specified, a base, a post rising from the base, a bracket hinged upon the post and adapted to swing in a vertical plane, a pair of driving members arranged concentrically in the bracket and adapted for adjustment into vertical position when the bracket is swung down, concentric driven members adapted to align with the driving members when the bracket is lowered, a sleeve carried by one of said driving members, a hub arranged within the sleeve and having connection with the opposite driving member, said hub and said sleeve being adapted for engagement over the upper ends of said concentric driven members and being adapted for disengagement therefrom by the upward swinging of the bracket.

3. A device as specified comprising a base, a leg integrally connected with the base, a plate connected to the base, a second plate having spaced legs connected thereto, means for connecting the plates together for forming a support for the base, a vertical post received between and supported by the plates, and operating means mounted upon the post for operation over the base.

4. A device as specified comprising a base, a vertical post connected thereto, clamping members connected to the upper terminal of the post, one of the clamping members having a recess therein, a bracket having a recess in which the terminal of said recessed clamping member is received, and a terminal on the bracket received in the recess of the clamping member, said bracket and recessed clamping member being provided with shoulders for limiting the rotary movement of the bracket on the recessed clamping member, means for connecting the bracket to the recessed clamping member and for holding the bracket in its adjusted position, driven means, and means carried by the bracket for transmitting rotary motion to the driven means.

5. In mechanism as specified, a support, a bracket hinged for vertical swinging on the support, concentric driving members mounted in the bracket and having a hub on one member and a sleeve on the opposite member, said sleeve surrounding the hub to inclose the same and providing therewith concentric sockets on the lower terminals of

said driving members, a pair of concentric driven members projecting at their upper ends into said sleeve, one of said driven members having interlocking engagement with the sleeve, and the opposite driven member having interlocking engagement with said hub, said driving and driven members being adapted to be disconnected by the upward and outward swinging of said bracket.

6. In mechanism as specified, a base, a post rising from the base, a bracket hinged for swinging movement on the post and adapted to swing down into a laterally extending position, a shaft journaled in the bracket adapted to extend vertically when the bracket is swung down and having a pinion fixed thereon, a loose pinion journaled in the bracket to turn about the shaft in an opposite direction thereto and having a depending hub, a sleeve carried by the hub and projecting downwardly beyond the lower extremity of said vertical shaft, a second hub arranged in the sleeve and having securing on the lower extremity of said vertical shaft to turn therewith in an opposite direction from the sleeve, a vertical driven shaft beneath the first shaft, and a tubular shaft surrounding the driven shaft, said driven shaft and said tubular shaft each projecting upwardly into said sleeve and being interlocked respectively with the second hub and with the sleeve, said second hub and said sleeve being adapted to be lifted up out of engagement with the driven vertical and tubular shafts upon the upward swinging of the bracket.

7. In combination with a support, driven members mounted in the support and projecting upwardly therefrom, a clamp adjustably mounted at one side of the support, and having an upstanding ear, a bracket overhanging the support, and having a depending ear for lapping engagement against said first ear, driving elements carried on the bracket, separable connections lying substantially in the same plane between said driving means and said driven members to admit the swinging upwardly and outwardly of the bracket from above the support to disconnect the driving means from said driven members, without disturbing the adjustments of the latter, and a clamping bolt passing through said ears for binding the same together to rigidly secure the bracket in any of its adjusted positions.

8. In combination with a support having driven members therein, a vertically and horizontally adjustable bracket mounted at one side of the support and having an upstanding ear, and a shoulder at each side of the ear, a bracket having a depending ear for lapping engagement against the first ear, and having a shoulder at each side of the bracket adapted to abut the correspond-

ing shoulders on the clamp ear to limit the vertical swinging of the bracket, a clamping bolt passing through the ears to bind the same together to secure the bracket in 5 adjusted position, a driving element in the bracket, and separable connections above the support between the driving element and the said driven members.

9. In combination with a support, driven 10 members in the support, a clamp mounted for vertical and horizontal adjustment at one side of the support, a bracket overhanging the support, overlapping ears carried upon the bracket and the clamp and 15 having recesses in their opposite sides to snugly receive the ear of the opposite member, shoulders at the opposite sides of the ears adapted to abut to limit the downward swinging of the bracket over the support, 20 and to limit the upward and outward swinging of the bracket, a clamping bolt for binding the ears together in their respective

recesses to firmly hold the bracket in adjusted position, a driving member in the bracket, and a separable connection between 25 the said driven members and the driving member adapted to separate substantially in the same horizontal plane with the pivotal engagement of said ears to admit of the upward and outward swinging movement of the bracket without disturbing the adjustment of the driven members in the support, said shoulders being adapted to abut to hold the bracket firmly in horizontal position, and prevent the binding of 30 35 said separable connections.

In testimony that I claim the foregoing as my own, I have hereto affixed my signature in the presence of two witnesses.

CHARLES JOHN ARMSTRONG.
